UNITED STATES PATENT OFFICE.

OSCAR A. NORDLUND, OF LINDSBORG, KANSAS, ASSIGNOR OF TWO-THIRDS TO N. P. NELSON, OF LINDSBORG, KANSAS, AND FRANK O. JOHNSON, OF MCPHERSON, KANSAS.

WRENCH.

1,072,767.

Specification of Letters Patent. Patented Sept. 9, 1913.

Application filed July 31, 1912. Serial No. 712,598.

To all whom it may concern:

Be it known that I, OSCAR A. NORDLUND, a citizen of the United States, residing at Lindsborg, in the county of McPherson and State of Kansas, have invented certain new and useful Improvements in Wrenches, of which the following is a specification.

My invention relates to new and useful improvements in wrenches and more particularly to that class of wrenches having a fixed jaw and a movable jaw mounted for adjustment relative to the fixed jaw, and the object of my invention is to provide a wrench of the above described character in which the movable jaw may be moved to adjusted position with respect to the fixed jaw and which, upon the application of power applied to the handle of the wrench, will be further moved toward the fixed 20 jaw, the active faces of the jaws at all times remaining parallel to each other.

A further object of my invention is to so construct the wrench that upon releasing the handle, the movable jaw will return to adjusted position automatically. And a still further object of my invention is to provide means for locking the movable jaw when swung toward the fixed jaw by the movement of the handle.

With these and other objects in view, my invention will be more fully described, illustrated in the accompanying drawing, and then specifically pointed out in the claims which are attached to and form a part of this application.

In the drawing: Figure 1 is a face view of the wrench; Fig. 2 is a similar view, the handle being shown in section to better show the construction and operation of the wrench; Fig. 3 is a fragmentary perspective view, showing a lock which may be employed in securing the movable jaw in place.

Corresponding and like parts are referred to in the following description and indicated in all the views of the drawing by the same reference characters.

The preferred embodiment of my invention includes a shank 10, preferably rectangular in section and provided at one end 50 with an integrally formed jaw 11 and a second shank 12, also preferably rectangular in section and provided with an integrally formed jaw 13 and a sleeve 14 through

which the shank 10 is movable and a compound handle including a handle member 55 15 rigidly secured to the shank 10 and a handle 16 pivotally secured to the same shank. The jaws 11 and 13 are each provided with a detachable plate 17 having a plurality of work engaging teeth 18, the 60 teeth of one plate being inclined oppositely to those of the other, as shown in the drawing. The shanks 10 and 12, as previously described, are preferably rectangular in section, but in any case the opposed faces 65 of the shank are shaped for sliding engagement with each other to permit the movement of the shank 12 and its jaw longitudinally upon the shank 10 to move the jaw 13 toward and away from the jaw 11. 70

The handle member 15 is preferably formed of heavy sheet metal of sufficient strength to withstand the strains to which it will be subjected and the metal forming this handle is bent upon itself longitudinally in 75 such a manner that the handle is substantially U-shaped in section and that that end of the handle which is secured to the shank 10 by a rivet or other suitable fastening means 19 forms a sleeve 20 for guiding the 80 free end of the shank 12 and maintaining the same in engagement against the shank 10. The handle 16 is also formed of heavy sheet metal in the same manner as the handle member 15 and that end of the handle 85 member 16 which is pivotally mounted as at 21 upon the shank 10, is provided with extensions 22 which project over the shank 12, one upon either side thereof, and the end portions of each of which are cut away 90 to provide spaced ears 23. Spacer blocks 24 are positioned between the spaced ears of one of the extensions 22 and the corresponding ears of the other of said extensions and are secured in place by rivets or other 95 suitable fastening means 25. A worm gear 26 is journaled by its reduced terminals 27 in suitable bores formed in these spacer blocks 24 and a thread 28 in this gear meshes with the spaced teeth 29 formed in the outer 100 face of the shank 12. The extensions 22 and ears 23 are so formed that the longitudinal axis of the worm gear 26 normally extends at an angle to the shank 12, the thread of said gear fitting loosely in the teeth of 105 the shank and the free end of the handle

member 16 extending at an angle from the shank 10. In order to maintain the handle in this position, I have provided a leaf spring 30, one end of which is secured to the back face of the shank 10 and the other end of which extends within the pivoted end of the handle 16, as shown.

As will be readily seen, if the free end of the handle member 16 is swung toward 10 the handle member 15, the engagement of the worm gear with the teeth of the shank 12 will cause the outward movement of the shank 12 along the shank 10 to move the jaw 13 toward the jaw 11.

15 In operation, the jaw 13 is roughly adjusted relative to the jaw 11 by turning the worm gear 26 in the customary manner. The wrench is then applied to the nut, pipe or other object and employed in the usual 20 manner. The strain thus exerted upon the handle member 16 will force the jaw 13 toward the jaw 11 and the greater the strain applied upon the handle and consequently the greater the force tending to spread the jaws 25 apart, the greater will be the force acting through the handle and worm gear to move the jaws together. As soon as the handle member 16 is released, the spring 30 immediately returns it to normal position with 30 respect to the shank 10 moving the jaw 13 out of engagement with the work operated upon.

In Fig. 3 I have shown a modified form of construction embodying an automatic lock 35 for securing the movable handle member 16 in active position to maintain the jaw 13 in advanced position. In this form of wrench, the upper ear 23 adjacent the free end of the handle member 16 is provided 40 with a perforation 31 so formed that when the handle member 16 is swung as far as possible toward the handle member 15, it will register with the space between adjacent teeth 29 of the shank 12. The ear 23 so 45 perforated is provided with a pair of spaced apart upwardly directed ears 32 and pivotally mounted intermediate its length between these ears, is a lever 33, one end of which carries a downwardly de- 50 pending pin 34 adapted to pass through the perforation 31 and engage between the teeth 29 of the shank 12 and to bear against the outerface of the shank 12, thereby preventing return movement of the handle 55 member 16. A helical spring 35 is mounted between the extended portion 22 of the handle member 16 and the free end of this lever to automatically force the pin into active position when the handle members 60 are drawn together. As will be readily seen, this not only serves to lock the handle members together and consequently the movable jaw in advanced position, but also serves to lock the wrench against any possible change in adjustment, due to unin-

tentional turning of the worm gear 26. The lever 33, being located as shown in Fig. 3, may be readily depressed against the action of the spring 35 by the thumb of the operator to release the lock at any desired time. 70

It will of course be understood that I do not wish to limit myself to the specific construction of the wrench handle or to the specific details of lock mechanism therefor as various changes in details may be made 75 at any time without departing from the spirit of my invention.

Having thus described the invention, what is claimed as new is:

1. A wrench including jaw carrying shanks, one of which is movable upon the other, said movable shank being provided at its jaw carrying end with a sleeve engaging about the other shank and upon its outer face with a plurality of spaced teeth, a 80 handle pivoted to the other shank and having extended portions bearing over the sides of the sleeve carrying shank and forming a second sleeve, and a worm gear journaled in blocks carried by the free ends of said 85 extensions and engaging the teeth of the shank.

2. A wrench including relatively movable jaw carrying shanks, one of which is provided with spaced teeth, a handle member 95 pivotally secured to the other of said shanks and having laterally directed extensions bearing against opposite faces of the shank having teeth and projecting beyond the same, a worm gear journaled between the 100 projecting portions of said extensions and meshing with the teeth of the shank, and a spring carried by the handle carrying shank and normally maintaining said handle at an angle to the shank and the gear at an angle 105 to its shank.

3. A wrench including relatively movable jaw carrying shanks, one of said shanks being provided with spaced teeth, a handle 110 swingingly mounted upon the untoothed shank, a worm gear carried by said handle and engaging the teeth of the other shank in such a manner that the swinging of the handle upon its shank will cause the toothed shank to move relatively to the handle carrying shank, and means carried by said handle and coacting with the teeth of the shank for locking the shanks against movement. 115

4. A wrench including relatively movable 120 jaw carrying shanks, one of said shanks being provided with spaced teeth, a handle swingingly mounted upon the untoothed shank, a worm gear carried by said handle and engaging the teeth of the other shank 125 in such a manner that the swinging of the handle upon its shank will cause the toothed shank to move relatively to the handle carrying shank, and means carried by said handle for locking the shanks against move- 130

ment, said means including a spring pressed lever carrying a pin movable into and out of engagement with the teeth of the shank.

5. A wrench including a shank provided at one end with an integral jaw and at its other end with a fixed handle, the intermediate portion of the shank having teeth formed on one face, a second shank movable along the opposite face of the first and terminating 10 at one end in an integral jaw and at its other end in a pivoted handle, the pivoted end of

the handle having an integral housing extending over and beyond the first shank, and a worm gear rotatably mounted in the housing for rocking engagement with the teeth 15 of the first shank.

In testimony whereof I affix my signature in presence of two witnesses.
